UNITED STATES PATENT OFFICE.

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY.

HEEL.

Application filed November 3, 1922. Serial No. 598,860.

To all whom it may concern:

Be it known that I, FRED ASHWORTH, a citizen of the United States, residing at Wenham, in the county of Essex and State 5 of Massachusetts, have invented certain Improvements in Heels, of which the following description, in connection with the accompanying drawings, is a specification, like reference characters on the drawings indicating like parts in the several figures.

This invention relates to heels and has particularly in view the attainment of increased economy and the production of a superior form of blank for incorporation 15 in a shoe heel, either as one of a plurality of lifts or as a base section for a rubber heel.

In order to aid in the production of a concavity or so-called "cup" in the base side 20 of a heel it has been a common practice to attach a rand to the face of the base lift of the heel. It is necessary that such a rand be made of high grade, firm material, and it is universal practice to use leather.

It is an object of the present invention to produce an article which is even superior to the conventional heel base with an attached rand, yet at a less manufacturing cost. To this end a heel lift is split around 25 its edge, opened, and the split filled with material which may be cheaper than an integral leather rand of good quality. The split edge of the lift may, for example, be filled with a rand-shaped piece of leatherboard or 30 even with a pieced rand made of leatherboard or scrap leather. The resulting blank is integral and unbroken on both faces and has the required depression or cup in its center. By reason of its unbroken seat face 35 it is superior even to a blank having a complete leather rand attached externally thereto.

The rand-shaped filling piece may be secured in the split edge of the lift by an 40 adhesive or other suitable means, and the blank may advantageously be molded to shape in a heel compressor. Such a blank is eminently satisfactory for use in a lift heel or for use, either alone or in combination 45 with another lift or lifts, as a base for rubber heels. In the illustrated embodiment of the invention a leather lift having its split edge filled with a rand-shaped piece of leatherboard is used as a base for

a rubber heel which is attached to a shoe 55 by nails passing through both the lift and the rand.

Further features and advantages of the invention will be understood and appreciated from reading the following detailed 60 description of one embodiment thereof in connection with the accompanying drawings, in which

Fig. 1 is a perspective view of a heel lift split around its edge, with the split opened 65 ready to receive a rand or filling piece;

Fig. 2 is a perspective view of a pieced rand ready for insertion in the split edge of the lift;

Fig. 3 shows the blank after it has been 70 assembled and molded in a compressing machine; and

Fig. 4 shows the heel end of a shoe with a rubber heel attached, upon the blank of 75 Fig. 3 as a base.

Referring now to the drawings, 10 indicates a lift, preferably of leather, which is split around the edge, as shown at 12, the split being opened to provide a space of wedge-shaped cross section. A rand-shaped 80 filling piece 14 is prepared to fit in the split edge of the lift 10. The rand 14 may be made of leatherboard, scrap leather or other suitable cheap material and may either consist of a single piece or may be pieced, as 85 shown, for example, at 16, Fig. 2.

The rand 14 may be secured in the split 12 by an adhesive or other suitable securing means and the blank may then be molded under heavy pressure to the desired form, 90 as illustrated in Fig. 3, where a concave or cupped face is shown at 18 and a Coburn lip at 20.

It will be noted that the blank thus produced has a continuous, unbroken face of 95 leather on each side. This is highly desirable in any heel and particularly so in a rubber heel base, for the reason that the chafing action between a rubber heel and the base to which it is secured is so pronounced as to cause disintegration of any material which is weaker than leather, while it has always been recognized that a surface of leather was best for attachment to the heel seat end of a sole. By this invention 100 there is produced from a single leather lift a blank having its edge thickened to the required degree with cheap material with-

out sacrificing the continuity of the leather surfaces of its two faces.

- The inserted rand or filling piece 14 may be sufficiently wide to permit the heel attaching nails 22 to pass through it, as shown in Fig. 4, thereby adding their holding power to that of the adhesive which may have been employed, and effectually insuring a secure retention of the rand in place.
- 10 The rubber heel 24 is in contact with a continuous surface of leather and is attached, as shown, by nails passing through the lift 10, rand 14, sole 26 and clinched in the inner sole 28.
- 15 By the use of this invention a very material economy is secured over the usual leather lift with a leather rand applied to its face, while the blank itself is even superior thereto, for the reasons previously
- 20 pointed out.

Having described the invention, what is claimed as new and desired to be secured by Letters Patent is:

1. A heel blank comprising a lift having its edge split and spread open, and a piece of material inserted in the space thus provided.
2. A heel blank thicker at the edge than in the middle, comprising a single thickness of material in the middle and a plurality of thicknesses at the edge, both faces of the blank being integral.
3. A heel blank comprising a lift having its edge split and spread open, and a piece of different material inserted in the space thus provided.

In testimony whereof I have signed my name to this specification.

FRED ASHWORTH.
